CLAIM

The ornamental design for a traction device, as shown and described.

DESCRIPTION

FIG. 1 is a front or back view of the traction device.

FIG. 2 is a right or left side view of the traction device.

FIG. 3 is a top view of the traction device.

FIG. 4 is a bottom view of the traction device; and,

FIG. 5 is an isometric view of the traction device.

The broken line showing of the hole in FIG. 4 on the traction device is included for the purpose of illustrating environmental structure and forms no part of the claimed design.
